CHARLES L. CHISHOLM, OF NEW GLASGOW, NOVA SCOTIA, CANADA; ALICE W. CHISHOLM, EXECUTRIX OF THE WILL OF SAID CHARLES LOGAN CHISHOLM, DECEASED, ASSIGNOR TO THE CHISHOLM DEVELOPMENT CO., INC., OF BOSTON, MASSACHUSETTS, A CORPORATION OF MASSACHUSETTS.

SOUND-REPRODUCING MACHINE.

1,411,235.

Specification of Letters Patent. Patented Mar. 28, 1922.

Application filed October 18, 1915, Serial No. 56,570. Renewed November 15, 1919. Serial No. 338,324.

To all whom it may concern:

Be it known that I, CHARLES L. CHISHOLM, a subject of the King of England, residing at New Glasgow, Province of Nova Scotia, Dominion of Canada, have invented a new and useful Sound-Reproducing Machine, of which the following is a specification.

This invention has reference to sound-reproducing machines, and more particularly to the sound-box structure. The object of the present invention is to provide a reproducer sound-box whereby certain characteristics of the recorded sounds not heretofore obtained in the reproduced sounds are included in such reproduced sounds, so that the sounds obtained from the sound record have a naturalness not heretofore attained.

It is known that sound records contain overtones to which sound-reproducing devices as heretofore constructed are not sensitive, so that the reproduced sounds have a different quality from the original sounds.

Id there is a noticeable difference between the reproduced sounds and the originals of the recorded sounds. The result is that a sound-reproducing machine in operation is readily recognized as such and is not mistaken for the original of the recorded sounds, wherefore the reproduction has a sound-reproducing machine quality of its own, because of the absence of over-tones in such reproduced sounds, although the over-tones are actually recorded in the sound record.

While the present invention is not directed to the recording of sounds, the perfection of the reproduction is dependent in part upon the perfection of the recording of the sounds. Such perfection in recording is due to a large extent to having the diaphragm of the recording sound box superficially free with the stylus arm in contact with the center of the diaphragm over an area of minute extent approaching as near as practicable to a geometric point. For the best results such arm should also be free from actual attachment to the diaphragm. Good results may be obtained even when a minute quantity of wax or the like is used to con-

nect the sides of the pointed end of the stylus to the central portion of the diaphragm, with, however, the extremity of the point in actual unattached contact with the diaphragm.

In the present state of the art sound records have the sound record grooves of sinuous form or varying depth. The sinuous form is known as a gramophone record and the form of varying depth is known as a phonograph record. These different kinds of sound records require styluses and stylus carrying means of different shapes and constructions for actuating the reproducing elements, which latter usually include a diaphragm for converting the variations of the sound record grooves into air waves simulating the original sound. The original sound record, the reproducing diaphragm, the stylus, and the means for transmitting the motions of the stylus to the diaphragm all have an influence upon the reproduced sound. It is due to the customary manner of connecting the stylus to the diaphragm for causing vibration of the latter that there is loss of the over-tones and the character of the reproduced sound is correspondingly modified, and the reproduced sounds therefore have a talking machine character to a greater or less extent.

It has been found that by transmitting the vibrations of the stylus to the diaphragm through the intermediary of electrical means after the manner of a telephone, many of the over-tones heretofore lost are impressed upon the reproducing diaphragm and the reproduced sound has the naturalness of the original sound, so that the reproduced sounds very closely simulate the original sounds to an extent noticeably superior to the commercial sound reproducing machines, with the advantage that such naturalness of reproduction from commercial types of sound records is commercially feasible.

The present invention contemplates the employment of a microphonic element, or, if need be, more than one microphonic element, located practically at or in some other relation to the stylus, while the vibrations imparted to the microphone by the stylus

are transmitted to the diaphragm through electromagnetic means similar to the action of a telephone receiver.

It is best to employ a microphonic element 5 of minute size to avoid material interference with the vibration of the stylus, and, furthermore such microphonic element should be free to move with or under the action of the stylus, so as to avoid material 10 dampening of the vibrations, and for this reason the microphone may be of an inertia type, whereby the variations of contact are brought about by an inertia action, as will hereinafter appear.

15 The present invention also contemplates the combining of the mechanical transmission of the vibrations from the stylus to the diaphragm with electrical transmission thereof, whereby the tones due to the mechanical transmission have superposed thereon over-tones due to the electrical transmission, so that loudness of reproduction with naturalness of reproduction is obtainable.

The invention contemplates numerous detail improvements which will appear hereinafter.

The invention will be best understood from a consideration of the following detailed description, taken in connection with the accompanying drawings forming part of this specification, with the further understanding that while the drawings show a practical form of the invention, the latter is not confined to any strict conformity with the showing of the drawings, but may be changed and modified, so long as such changes and modifications come within the scope of the appended claims.

In the drawings:—

40 Figure 1 is an elevation of a sound box equipped for electrical transmission to the diaphragm of the impulses imparted to the stylus by the sound record.

45 Figure 2 is a section on the line 2—2 of Figure 1 with some parts in elevation, and also showing electrical connections diagrammatically.

50 Figure 3 is a view similar to Figure 1 but illustrating a sound box equipped with both mechanical and electrical transmission of vibrations from the stylus to the diaphragm.

Figure 4 is a section on the line 4—4 of Figure 3 with some parts in elevation.

55 Figure 5 is an end elevation of the diaphragm actuating magnet and stylus arm of Figures 3 and 4, the diaphragm being shown in section.

60 Figure 6 is a perspective view of the upper end of a cabinet type of sound reproducing machine showing the invention applied.

65 Figure 7 is a view similar to Figure 2 showing a somewhat modified form of the invention with the electrical circuits in dia-

Figure 8 is a section lengthwise of the stylus arm and microphonic element utilized as a holding screw for the stylus in accordance with the showing of Figure 1, the drawing being on a considerably magnified scale. 70

Figure 9 is a side elevation of a microphonic element with parts broken away to show some of the internal construction, the scale being also considerably magnified.

Referring to the drawings there is shown 75 a sound box casing 1 carrying a diaphragm 2 and provided with the usual neck 3 at the back of the casing for the attachment of the sound box to the swinging arm element 4 of the sound amplifier of the instrument. So 80 far as the sound box and its support, together with a sound amplifier, are concerned, such parts may follow the usual practice of well known commercial machines, and while in the drawings the types of 85 sound boxes shown are those adapted for the gramophone type of sound record, it will be understood that by well understood changes in construction the phonograph type of sound record and sound box may be utilized. The characteristics of the different 90 types of commercial sound reproducing machines are so well known that it is not deemed necessary to illustrate the phonograph type, since the invention will be fully 95 understood from the forms shown in the drawings.

In Figure 1 a rock arm 5 is mounted upon the sound box by means of trunnions 6 and bearing screws 7 constituting the well known 100 pointed bearing employed in many delicate instruments.

The screws 7 extend through lugs 8 on the sound box 1, after the customary manner, so that the arm 5 may have an extent of rocking movement about the axis of the trunnions 6. The arm 5 at the end remote from the sound box, since such arm projects beyond the periphery of the sound box, is formed into an elongated socket 9 designed 105 to receive a reproducing stylus 10 which in the drawings is shown as of the customary steel needle type, although, of course, the fiber type of stylus may be used or the jewel type or any other form of stylus employed 110 in sound reproducing machines. In the case of the employment of the needle type of stylus, it is necessary to frequently renew the stylus, wherefore the styluses are made readily removable from the stylus arm and are ordinarily held in the socket 9 by a set or clamp screw easily operable by hand. In the structure shown in Figure 1 there is a microphonic element 11 employed as the clamp screw for the stylus, such microphonic 115 element being shown on a greatly enlarged scale in Figure 8. The microphonic element is provided with a casing 12 containing a back contact 13 and a front contact in the form of a diaphragm 14 carried by the casing and 120

defining between the diaphragm and the back contact a granule chamber containing a suitable amount of granules 15 usually of carbon and following the customary telephone practice. The casing 12 has on the side of the diaphragm remote from the granule chamber and in spaced relation to the diaphragm a cover member 16 which may be a simple plate, and this cover member is held 5 to the casing in any suitable manner, as, for instance, by a spun-over edge 17 of the casing. Since it is convenient to employ the cover 16 as an electric conductor, insulation 18 is introduced between the edge of the cover 10 and the casing, although, of course, it will be understood that since it is not obligatory to use the cover as an electric conductor the insulation may in such case be omitted. The cover 16 in the particular showing of Figure 15 8 is connected to the back contact 13 by an insulated conductor 19 soldered or otherwise joined to a projection 20 on the back contact, such projection being, of course, suitably insulated from the casing. Secured to 20 the diaphragm 14 is a stem 21 having a threaded portion adapted to screw into the socket end 9 of the stylus arm 5 in order to clamp the stylus 10 in readily removable relation to the socket. The stem 21 is ex- 25 tended through a passage 22 in the cover 16, so that electrical connection between the stem 21 and cover 16 is prevented.

Since the diaphragm 14 is utilized as one terminal of the microphonic element the 30 stem 21 being fast to the diaphragm and being made of metal is utilized as a conductor electrically connecting the diaphragm with the stylus arm 5 and the latter may also be used as a conductor, as will hereinafter appear. The utilization of the cover 16 as one 35 terminal of the microphone and the use of the microphone as a binding screw for the stylus necessitates a contact with which the cover may engage. Such a contact is shown 40 in Figures 2 and 8 as an elastic member 23, which may be in the form of a strip of metal bent upon itself with one end fast to but electrically insulated from the stylus arm 5 and the other so situated that when the 45 microphonic element is screwed so that the stem 21 clamps the stylus 10 the strip 23 is in engagement with the cover 16 preferably under some elastic pressure, thus insuring good contact. A conductor 24 is made fast 50 at one end to the strip 23 and is included in a circuit to be described. The stylus arm 5 is maintained in a central or neutral position by an equalizer spring 25 which may be made fast to the sound box casing 1 and 55 extend to opposite sides of the axis of rocking of the arm 5 so that the arm is centralized or equalized by the spring, but will readily rock under impulses imparted to the stylus 10 by the sound record groove.

60 The microphonic element is supported

solely by the stem 21, which in turn is carried by the stylus arm. Therefore, when the stylus is vibrated by the sound record groove such vibration is imparted to the diaphragm 70 14 and because of the inertia of the microphone the granules are subjected to compression and released therefrom in a manner similar to the action of a microphonic element when the casing is held rigidly and the diaphragm is vibrated.

However, by mounting the microphonic element upon the stylus arm close to the stylus, that is, between the support for the stylus arm and the record engaging end of the stylus, the microphone is subjected to 80 violent agitation without undue dampening effect upon the stylus, although the stylus arm constitutes the sole support for the microphonic element through the connecting stem in turn connected to the diaphragm of 85 the microphone.

The microphonic element may be made minute since excellent results are obtained when the microphonic casing is one-half to five-eighths of an inch in diameter and 90 about three-sixteenths of an inch thick. While the actual weight of the microphonic element is small it is so constructed that it has sufficient inertia to cause relative movements of the microphone diaphragm with 95 respect to the body of the microphone to cause the desired action of the microphone. It is because the microphone is mounted to act in the manner described that it is termed an inertia microphone, thereby distinguishing it from microphones in which the body of the microphone is rigidly secured to a support or mounting. The inertia microphone has the advantage of producing far less dampening effect upon the stylus than a 100 105 microphone otherwise mounted and the beneficial effects obtained by the microphone far outweigh any detrimental effects due to the mounting of the microphone upon the stylus arm, this being especially true when the 110 microphone is mounted between the support for the stylus arm and the active end of the stylus.

Extending across the sound box casing 1 is a bridge piece 26 to which is secured an 115 electromagnet 27 having a pole piece 28 in close relation to the face of the diaphragm 2 at the center portion of the latter. The microphone and electromagnet are suitably electrically joined so that electrical undulations produced in the circuit by movements of the microphone imparted thereby by the stylus cause vibrations of the diaphragm 2 in accordance with the variations in the sound record groove.

120 The actual operation of a structure built in accordance with the showing of Figures 1 and 2 has demonstrated that the reproduced sounds have a naturalness not obtainable in sound reproducing machines where 130

the vibrations of the stylus are mechanically imparted to the sound box diaphragm and, furthermore, the reproduced sounds have been found to be superior in naturalness 5 to electrically operated reproducing diaphragms where the microphones have been so situated as to have a material dampening effect upon the vibrations imparted to the stylus by the sound record groove. The superior 10 results obtained are believed to be due to the employment of the inertia microphone and to the mounting of the microphone so as to receive the impulses of the reproducing stylus without transmission through 15 a considerable distance before reaching the microphone, and hence losses due to mechanical conditions are avoided.

In Figure 2 the electrical connections between the microphone and the electromagnet 20 27 are diagrammatically indicated. The magnet 27 has one side connected directly to metal parts of the sound box as by a conductor 29 connected to the bridge piece 26, while the other side of the magnet 27 is connected by a conductor 30 to a battery 31 which may be taken as representative of any suitable source of current. The battery 31 is shown as connected by a conductor 32, including a switch 33, to one side of a rheostat 34, while the other side of the rheostat is connected by a conductor 35 to a switch 36 having in the path of its arm the terminals of two conductors 37, 38. The conductor 37 is connected to a volt meter or other suitable 30 indicating instrument 39, the other side of which is connected to the conductor 24. The conductor 38 is bridged about the instrument 39 so that the latter may be included in or cut out of circuit without affecting 40 the continuity of the circuit.

Considering the switch 36 as coupled to the conductor 38 with the rheostat 34 adjusted to the zero point and the switch 33 closed, the circuit may be traced from the battery 45 31, through switches 33 and 36, conductor 38, conductor 24, spring member 23, cover 16, conductor 19, back contact 18, granules 15, diaphragm 14, stem 21, stylus arm 5, sound box 1, bridge piece 26, conductor 29, winding of the electromagnet 27 and conductor 30, back to the battery 31. Such an arrangement when in operation causes the production of a variable current in the electric circuit and a corresponding variation in 50 the magnetic effect of the electromagnet 27, especially if the pole piece 28 be a permanent magnet. Under the conditions assumed the microphone and electromagnet are subjected to the full power of the battery 31 as 55 modified by the variations by resistance in the microphone. In order that an operator of the sound reproducing machine may produce modifications in the reproduction of the sound, the rheostat 34 is provided, 60 whereby extra resistance is introduced into

the circuit and the effect of the battery is correspondingly reduced, so that the reproduced sound may be materially modified and softened.

Since an electric battery will be the usual 70 source of electric current, such battery is liable to weakening by use, and, therefore, an electric measuring instrument 39, shown as a volt meter but which may be any other type of electric measuring instrument, is provided so that an operator may ascertain 75 at any time the condition of the battery and if the reproduced sound is not of the character expected the operator may quickly ascertain whether the fault is in a weakening 80 of the battery. The volt meter need be used but momentarily, since the switch 36 provides for the cutting in and out of the volt meter, at will.

In Figure 6 there is shown a cabinet 40 85 containing a sound reproducing machine which may be considered as provided with a sound box 1 having a diaphragm 2, a microphone 11 and an electromagnet 27. The cabinet is shown as provided with the usual cover 41 and with a turntable 42 carrying a record tablet 43. In such a cabinet there is room for placing the battery 31 of which a storage battery will be found to be a convenient form. The rheostat 34 is conveniently mounted within the cabinet in accessible position and the volt meter 39 is also conveniently mounted within the cabinet in accessible position for observation. 95

The structure of Figures 1 and 2 may be included 100 in a cabinet form of machine shown in Figure 6 or in any other type of sound reproducing machine, and the same is true of other forms of the invention to be described.

In Figure 3 those parts similar to the structure of Figure 1 are designated by the same reference numerals. The principal difference between the structures of Figures 1 and 3 is that in the structure of Figure 3 110 means for the mechanical transmission of the stylus vibrations to the diaphragm 2 are included, so as to operate in conjunction with the means for the electrical transmission. The stylus arm 5 is replaced by a 115 stylus arm 5^a which may have the same kind of mounting as the stylus arm 5 and the corresponding parts are designated by the same reference numerals as in Figure 1. The stylus arm 5^a, however, has a continuation 44 continued to the center of the diaphragm and there provided with a bent terminal 45 having a pointed extremity 46 bearing against the central portion of the diaphragm. The point 46 approaches as closely 120 to a geometric point as is feasible, since theoretically the geometric point is the ideal form. Experience has shown that a broad contact and relatively rigid attachment of the stylus arm with the central portion of 130

the diaphragm is materially detrimental to the attainment of the best results and a reduction of such contact as well as the elimination of fixed connection between the stylus 5 arm and the diaphragm is conducive to far superior results. It is for this reason that the pointed end of the stylus arm where engaging the reproducing diaphragm is made of as small area as practicable and junction 10 means are avoided. For the best effects in the mechanical transmission of the vibrations to the diaphragm the extremity of the pointed ends of the stylus arm should be in actual contact with the diaphragm without the interposition of any wax or the like and the point where contacting with the diaphragm 15 should be of the smallest practicable area.

In the structure of Figures 3 and 4 a spring 25^a is used to constrain the pointed 20 end 46 of the stylus arm toward the diaphragm to maintain the stylus arm at all times in contact with the diaphragm. To show that it is not necessary to employ the microphonic element as a binding screw for 25 the stylus, the microphonic element 11 in the structure of Figures 3 and 4 is attached to the stylus carrying end of the arm 5^a close to the stylus, the attachment being by a stem 21^a which may be of considerably 30 smaller diameter than the stem 21 of Figures 2 and 8, although any particular size is not obligatory. In the structure of Figures 3 and 4 a thumb screw 47, such as is customarily used, is applied to the socket end 35 9 of the stylus arm to hold the stylus 10 in place and the microphone 21^a is mounted on the socket end 9 of the side of the latter remote from the thumb screw 47. Since it is desirable that the impulses imparted to 40 the diaphragm be applied thereto as close as possible to the center of the diaphragm the electromagnet 27 has a split pole piece 28 straddling the bent end 45 of the stylus arm 44. Otherwise the structure may be 45 similar to that of Figure 1.

Since in the structures described the diaphragm 2 is actuated by an electromagnet, such diaphragm is either made wholly of iron or has an iron armature where under 50 the influence of the electromagnet. For acoustical reasons it is preferred to have the diaphragm 2 wholly of iron and such diaphragm may follow telephone practice. The electrical connections of the structures 55 of Figures 3 and 4 may be the same as that of Figures 1 and 2 or may be such as is hereinafter described with reference to Figure 7. The microphone 11 of Figures 3 and 4 is shown in Figure 9 where the stem 21^a 60 is indicated as of smaller diameter than the stem 21, but otherwise the microphonic element may be the same as that of Figures 1 and 2, except for the omission of the contact member 23, which is not necessary in the structure of Figures 3 and 4.

The inertia characteristic of the microphone may be utilized in a manner similar to the showing of Figure 7, in which there is indicated a sound box frame 1, diaphragm 2 and neck 3 of the sound box. The stylus 5 arm 5^b mounted on trunnions 6 is shown in Figure 7 and the stylus arm is provided with a stylus socket 9 adapted to receive a stylus 10, the socket having a thumb screw 47^a similar to the thumb screw 47 of Figures 75 3 and 4. The stylus arm has an extension 44^a on the side of its support remote from the stylus and such stylus arm extension 44^a may reach to about the center of the diaphragm, although it is neither connected 80 to nor touches the diaphragm. A centralizing spring 25^a similar to the centralizing spring 25 of Figures 1 and 2 may be employed to hold the stylus arm in a normally neutral position. At the end of the arm 44^a 85 opposite the central portion of the diaphragm the arm carries a microphonic element 11 by a stem 21^a attached to the diaphragm of the microphonic element similarly to the showing of Figure 9. The 90 microphonic element therefore operates as an inertia microphone in the manner already described, wherein a diaphragm or vibratile member acts directly upon the resistance element being assisted in its action under 95 vibratile impulses imparted to the stylus, by the inertia of the microphonic structure. It will be understood that while the vibratile element of the microphone has been described as a diaphragm, other forms of 100 vibratile elements or contacts may be used, although the diaphragm is to be preferred. Like the microphone elements shown in the other embodiments of the invention, the microphonic element 11 of Figure 7 is wholly 105 supported by the stem 21^a attached to the end 44^a of the stylus arm remote from the stylus. Since the microphone element is located about opposite the center of the diaphragm and relatively close thereto, sufficient 110 room does not remain for the electromagnetic device to vibrate the diaphragm 2. Therefore, in the structure of Figure 7 an electromagnet 27^a is mounted in the neck 3, so that its polar extremities 28^a are in operative relation to the diaphragm, but on the face thereof remote from this microphonic element. In Figure 7 the electromagnet 27^a 115 is of the horseshoe type, while in the other figures it is shown as of the single pole 120 type, but it will be understood that either type may be used in any of the structures, the horseshoe type having the advantage of greater attractive strength.

In the showing of Figure 7 a somewhat 125 different arrangement of the electric circuits is provided. The conductor 24 leading from one side of the microphone 11 is connected to one end of the primary winding 48 of an induction coil 49, the other end 130

of the primary winding being connected by a battery 31, which in turn is connected to a rheostat 34, and the latter is connected by a switch arm 36 to either one of two conductors 37, 38 of which the conductor 37 is connected to an indicating instrument 39 and the circuit is then continued by a conductor 50 to some metallic part of the sound box. The electromagnet 27^a is connected on one side to the sound box and on the other side by a conductor 30 to one end of the secondary winding 51 of the induction coil 49, the other side of this winding being connected to the conductor 50 all in the manner common to telephone installations. In this way the microphone 11 sets up an alternating current in the electromagnet 27^a similarly to the current set up in an ordinary telephone receiver.

20 It will be understood that the electrical installation of Figure 7 may be followed in the structures of Figures 1 to 4, or in any other embodiment of the invention.

The particular type of sound box is not material to the present invention, nor is the particular type of sound record, and hence no attempt has been made in the drawings to show the various types of sound boxes or sound records, all of which are well known. 25 Some of the principal features of the present invention include the minute microphonic element, the arrangement of the microphonic element with relation to the reproducing stylus and the mounting of the microphonic element so that it has the least amount of dampening effect upon the reproducing stylus and the inertia of the body of the microphonic element is utilized, and the combination of mechanical and electrical 30 transmission to the stylus vibrations from the record to the sound reproducing diaphragm.

The invention is applicable to sound reproducing machines of all sizes and designs, 45 whether of the disk or cylinder type or of the gramophone or phonographic type.

While the microphonic element has been described as an inertia microphone of the granular type and also as provided with a diaphragm with a stem by which the microphonic element is wholly supported, it is to be understood that the invention is not necessarily confined to such particular type or construction of microphone, especially 50 with respect to some of the features of the invention. It is possible to obtain good results with microphonic elements of other than the granular type, or with a kind not provided with a diaphragm or with a kind 55 otherwise supported than by a stem or with a kind where the inertia characteristic is due to other means than the body of the device.

Again, the invention is not confined to mounting the electromagnetic actuating

means for the sound-box diaphragm upon 65 the sound-box, for it may be otherwise mounted so long as it maintains the proper relation to the sound-box diaphragm.

In accordance with the present invention means are provided whereby the electric energy employed may be varied at will, so that the resultant effect in audible sound is that of crescendo and diminuendo in any shade of strength within the capacity of the instrument. By properly constructing the 75 rheostat 34 so that its changes are gradual, either continuously or by small steps in waves well understood by electrical engineers, the gradations in the reproduced sounds may be sensibly continuous throughout 80 the range of the rheostat. In the drawings the showing of the rheostat is merely conventional and it is to be understood that any type of rheostat suitable for the purposes of the present invention may be employed.

In some types of sound reproducing machines gradation in the reproduced sounds is accomplished by the employment of varieties of styluses. In other sound reproducing machines the styluses are not changeable, and in such cases it has been proposed to produce gradations of the reproduced sound by damper or other mechanical structures.

With the present invention the gradation 95 is performed as gradually as desired, and without in any manner interfering with the free course of the air waves from the sound box to the external air.

The rheostatic control has the advantage 100 of changing the power of the reproduced sounds at will to any extent throughout the range of adjustment and with any type of sound reproducing instrument without requiring any change in the sound reproducing elements. The rheostatic control has the further advantage in that it may be operated at the sound reproducing instrument or at any point outside of or distant therefrom, and the effects of changes in the rheostat 110 are instantaneously apparent in the reproduced sound.

What is claimed is:—

1. Means for the reproduction of recorded sounds, comprising a sound reproducing diaphragm, electro-magnetic means for actuating it, a stylus arm with a stylus receiving portion, and a microphonic element electrically connected to the electromagnetic means and provided with a support constituting a 115 clamping means for holding a stylus in the stylus arm.

2. Means for the reproduction of recorded sounds comprising a sound reproducing diaphragm, electromagnetic means for actuating the diaphragm, a stylus arm with a portion adapted to receive a reproducing stylus, and a microphonic element electrici- 120 125

cally connected to the electromagnetic means and having a threaded stem entering the stylus arm to clamp the stylus thereto.

3. Means for the reproduction of recorded sounds comprising a sound reproducing diaphragm, electromagnetic means for actuating the diaphragm, a stylus arm with a portion adapted to receive a reproducing stylus, and a microphonic element electrically connected to the electromagnetic means and having a threaded stem entering the stylus arm to clamp the stylus thereto, said stem constituting the sole support for the microphonic element, whereby the inertia of the microphonic element is utilized in the production of the microphonic effect.

4. Means for the reproduction of recorded sounds comprising a sound reproducing diaphragm, a stylus carrier having a portion adapted to temporarily receive a reproducing stylus, electromagnetic means in operative relation to the diaphragm for vibrating it, and a microphonic element electrically connected to the electromagnetic means and provided with a screw constituting the clamp screw for the reproducing stylus and also the sole support for the microphonic element.

5. A sound box for sound reproducing machines provided with a sound reproducing diaphragm, electromagnetic means for actuating the diaphragm, a rockable stylus arm mounted on the sound box with one end of the stylus arm adapted to receive a reproducing stylus, and a microphonic element for controlling the electromagnetic means and mounted on and supported solely by the rockable arm between the axis of rocking of the arm and that end of the arm adapted to receive the reproducing stylus.

6. Means for the reproduction of recorded sounds comprising a sound box having a sound reproducing diaphragm, electromagnetic means mounted to be in actuating relation to the diaphragm, a rockable arm mounted on the sound box, yieldable constraining means in operative relation to the stylus arm for maintaining it in a neutral position, and a microphonic element mounted on the stylus arm and electrically connected to the electromagnetic means.

7. Means for the reproduction of recorded sounds comprising a sound box having a sound reproducing diaphragm, electromagnetic means in actuating relation to the diaphragm, a rockable stylus arm carried by the sound box, and an inertia microphonic element connected to and controlling the electromagnetic means and carried solely by the stylus arm.

8. Means for the reproduction of recorded sounds comprising a sound box having a sound reproducing diaphragm, a stylus arm in operative relation to the diaphragm to mechanically vibrate it, and electrically op-

erated means for vibrating the diaphragm in operative relation to the stylus arm to cause the diaphragm to respond to the combined action of the mechanical and electrical means under impulses imparted thereby by the stylus.

9. Means for the reproduction of recorded sounds, comprising a sound box having a sound reproducing diaphragm, a stylus arm mounted on the sound box in operative relation to the diaphragm to mechanically vibrate it, electromagnetic means movable with sound box in operative relation to the diaphragm to electromagnetically vibrate it, and a microphonic element mounted on the stylus arm for vibration thereby, and electrically connected to the electromagnetic means, whereby both the mechanical and electrical impulses produced by the vibration of the stylus are caused to simultaneously act upon the diaphragm to vibrate it.

10. Means for the reproduction of recorded sounds comprising a sound box with a sound reproducing diaphragm, a stylus arm mounted on the sound box in operative relation to the diaphragm to mechanically vibrate it, electromagnetic means mounted on the sound box in operative relation to the diaphragm to vibrate it, and a microphonic element mounted on the stylus arm adjacent to the stylus end thereof and electrically connected to the electromagnetic means, whereby the vibrations of the stylus are both mechanically and electrically imparted simultaneously to the diaphragm.

11. Means for the reproduction of recorded sounds, comprising a sound box having a sound reproducing diaphragm, a stylus arm carried by the sound box in operative relation to the diaphragm for mechanically vibrating it in accordance with the vibrations imparted to the stylus by the sound record, electromagnetic means in operative relation to the diaphragm for vibrating it, and an inertia microphonic element electrically connected to the electromagnetic means for controlling said means and supported solely by the stylus arm.

12. Means for the reproduction of recorded sounds comprising a sound box having a sound reproducing diaphragm, a vibratile stylus arm carried by the sound box in operative relation to the diaphragm for mechanically vibrating it in accordance with the vibrations imparted to the stylus by the sound record, electromagnetic means in operative relation to the diaphragm for vibrating it, and an inertia microphonic element electrically connected to the electromagnetic means for controlling said means and supported solely by the stylus arm, the microphonic element being mounted on the stylus arm between its axis of vibration and the stylus end of the stylus arm.

13. A structure for the reproduction of sounds from sound records, comprising means for setting air into vibration, mechanical means responsive to a sound record for actuating the air vibrating means in accordance with and by the sound record, and electric means associated with the mechanical means and with the air vibrating means for actuating the latter simultaneously with the actuation thereof by the mechanical means.
14. A sound box for sound reproducing machines provided with a sound reproducing diaphragm, electromagnetic means for actuating the diaphragm, a rockable stylus

arm mounted on the sound box, and a microphonic element for controlling the electromagnetic means and mounted on and supported by the rockable arm between the axis of rocking of the arm and the stylus carrying part thereof.

20 In testimony that I claim the foregoing as my own, I have hereto affixed my signature in the presence of two witnesses.

CHARLES L. CHISHOLM.
